(57) **CLAIM**

The ornamental design for a service module for a robot, as shown and described.

DESCRIPTION

FIG. 1 is a side elevation view of our new design for a service module for a robot;

FIG. 2 is a front elevation view thereof;

FIG. 3 is a front perspective view thereof; and,

FIG. 4 is a side elevation view thereof, installed in a robot. The broken lines showing a robot in FIG. 4 are environmental and form no part of the claimed design. All other broken lines illustrate portions of the service module and also form no part of the claimed design.
